TOY MOWING DEVICE

Edmund W. Baggott, Brooklyn, N. Y., assignor to
 Ideal Novelty & Toy Co., Hollis, N. Y., a corpora-
 tion of New York

Application September 25, 1948, Serial No. 51,279

2 Claims. (Cl. 46—39)

1

This invention relates to toy vehicles and is more especially concerned with a toy mowing device.

A primary object of the invention is the provision of a toy mowing device having a laterally extending cutter blade assembly including a reciprocatory cutter blade adapted for automatic actuation by the propulsion of the device.

A further object of the invention is the provision of a toy mowing device of the character indicated wherein reciprocatory motion is imparted to the cutter blade through the instrumentality of cam means fixed to and rotatable with the wheel shaft of the device.

Another object of the invention is the provision of a toy mowing device wherein the cutter blade assembly may be elevated to inoperative vertical position in realistic simulation of an actual mowing device.

An additional object of the invention is the provision of a toy mowing device of the character indicated which may be fabricated inexpensively from a minimum number of parts which may be readily molded from any suitable synthetic plastic material.

The foregoing objects as well as additional objects and advantages of the invention will be readily apparent in the course of the following detailed description taken in connection with the accompanying drawings which illustrate a preferred embodiment of the invention, and wherein:

Fig. 1 is a top plan view of the toy mowing device;

Fig. 2 is a sectional view taken on line 2—2 of Fig. 1;

Fig. 3 is a bottom plan view;

Fig. 4 is a view, partly in section and partly in elevation, taken along line 4—4 of Fig. 1; and

Fig. 5 is a sectional detail view taken along line 5—5 of Fig. 3;

Fig. 6 is a fragmental side view showing the cutter blade assembly locked in its inoperative position.

Referring now to the drawings in greater detail, the toy mowing device includes a frame 10 which is preferably molded as a unitary structure comprising an elevated seat 11, a footrest 12, a pair of shaft bearings 13, and a forwardly extending tongue portion 14, terminating in a coupling 14a, by means of which the device may be drawn along a supporting surface.

A shaft 15 is rotatably mounted in bearings 13 of frame 10 and wheels 16 are fixed to the ends of said shaft. Fixed to shaft 15 intermediate its ends is a cam wheel 17 defining a plurality of

2

fluted or sinusoidal cam surfaces 17a for imparting oscillating motion to a connecting lever 18 pivoted at 19 to the underside of frame 10 and engaging cam wheel 17 by means of a pair of lugs 20. Lever 18 may be further supported by means of a cross member 21 secured to frame 10. Lever 18 protrudes forwardly through a slot 22 in frame 10 and terminates in a bifurcated portion 18a provided with a pair of depending legs 18b in order to impart reciprocatory motion to the sliding cutter blade of the device in a manner to be fully described hereinbelow.

The device is provided with a cutter blade assembly, generally designated by reference numeral 23, which is preferably affixed to frame 10 in such a manner as to be swingable from an operative horizontal position to an inoperative vertical position. In the illustrated preferred embodiment the cutter blade assembly 23 comprises a fixed blade 24, having projections 25 in simulation of teeth, which supports the slidable, reciprocatory blade 26 having tooth projections 27. Fixed blade 24 is preferably provided along its rear edge with an upstanding guide rail 28 and is formed adjacent its free end with a transverse U-shaped guide member 29 slidably retaining the outer end of reciprocatory blade 26. A depending leg 30 is preferably formed integrally with blade 24 for supporting the cutter blade assembly 23 on the ground surface in the operative position of Figs. 1 and 2.

Fixed blade 24 is formed adjacent frame 10 with an inclined wall portion 31 terminating in a bearing portion 32 by means of which cutter blade assembly 23 may be swingably mounted on a longitudinal pivot shaft 33 preferably formed integrally with frame 10. As clearly shown in Fig. 2, a securing member 34 may be fixed adhesively or in any other desired manner at the open end of bearing portion 32 to complete the mounting of cutter-blade assembly 23 on pivot shaft 33, thereby preventing separation of said assembly from the frame 10.

Inclined wall portion 31 is provided adjacent fixed blade 24 with a transverse guide slot 35 slidably retaining the inner end of reciprocatory blade 26. Said reciprocatory blade 26 carries an arm 36 having a rearwardly extending pin 36a engageable between the depending legs 18b of bifurcated portion 18a of the cam-actuated oscillating lever 18 for imparting reciprocatory motion to said blade.

Thus, as the device is drawn along the ground, cam wheel 17 rotates with wheel shaft 15 to oscillate connecting lever 18. The oscillation of

said connecting lever is accompanied by the reciprocation of slidable blade 26 as a result of the operative connection between said connecting lever and said slidable blade in the horizontal operative position of the cutter blade assembly 23 illustrated in Figs. 1 and 2.

When it is desired to swing cutter blade assembly 23 to vertical inoperative position, a handle knob extension 37 fixed to guide member 29 may be employed. In order to limit the rotation of cutter blade assembly 23 about its pivot 33 a stop-projection 38 is formed on inclined wall 31, said stop-projection being received, in the vertical position of the cutter blade assembly, between a pair of suitably disposed projecting lugs 39 provided on frame 10. Bifurcated portion 18a of oscillating lever 18 is preferably provided with an arcuate guiding arm 40 against which pin 36a of slidable blade 26 abuts in order to locate said pin in proper alignment between depending legs 18b when the cutter blade assembly 23 is dropped from its inoperative vertical position to its operative horizontal position.

The device is preferably provided with locking means of any suitable conventional construction for releasably engaging cutter blade assembly 23 in its inoperative vertical position.

As slidable cutter blade 26 reciprocates its teeth 27 move into and out of registration with the teeth 25 of fixed blade 24 thereby simulating the cutting action of an actual mowing machine with startling verisimilitude. The registering position of slidable blade 26 and teeth 27 is indicated in full lines in Fig. 2 while the broken line position illustrates the limiting non-registering position of said slidable blade and teeth.

Since certain modifications may be made in the toy device of the invention without departing from the scope thereof, it is intended that all matter contained in the foregoing specification and shown in the accompanying drawing be interpreted merely as illustrative and not in a limiting sense.

What is claimed is:

1. A toy mowing device comprising a vehicle frame having a longitudinal axis, a shaft rotatably mounted on said frame, supporting wheels fixed to said shaft, a cutter blade assembly swingably mounted on said frame for rotation from an operative horizontal position to an inoperative vertical position, cam means fixed to and rotatable with said shaft, said cutter blade assembly comprising a fixed toothed bar and a slidable toothed bar supported thereupon, an oscillating lever, means pivotally securing said lever to said frame, coupling means coupling one end of said lever to said cam means, the other end of said lever being bifurcated and having a pair of depending leg portions, said slidable cutter bar having an extension releasably engageable between the bifurcated leg portions of said oscillating lever, whereby to impart reciprocatory motion to said slidable cutter bar in the operative position of said cutter blade assembly upon propulsion of the device along a supporting surface.

2. A toy device in accordance with claim 1, wherein said oscillating lever is provided with an arcuate guiding arm for alignment of the extension of said slidable cutter bar upon rotating said cutter blade assembly from inoperative vertical position to operative horizontal position.

EDMUND W. BAGGOTT.
